UNITED STATES PATENT OFFICE.

HERBERT J. PENDRAY, OF VICTORIA, BRITISH COLUMBIA, CANADA.

STATION INDICATOR.

1,417,765.

Specification of Letters Patent. Patented May 30, 1922.

Application filed April 17, 1919. Serial No. 290,758.

To all whom it may concern:

Be it known that I, HERBERT J. PENDRAY, a citizen of the Dominion of Canada, residing at Victoria, in the Province of British Columbia, Canada, have invented certain new and useful Improvements in Station Indicators, of which the following is a specification.

This invention relates to a station indicator of that class which is operated by the conductor of a train or street car to display to the passengers the name of the next station or street at which the car is empowered to stop.

15 The invention is fully described in the following specification, reference being made to the drawings by which it is accompanied, in which:

20 Fig. 1 is a vertical cross section showing the arrangement of the name band and its winding and display rollers with the casing.

Fig. 2 is a face view of the indicator to a reduced scale as exhibited to the passengers.

25 Fig. 3 is an end view to an enlarged scale showing the mechanism by which the indicator is operated.

Fig. 4 is a detail showing the frictional connection of the driving gear with each winding roller, and

30 Fig. 5 is a detail of the detent bolt by which the swinging plate is secured in its several positions.

In these drawings 2 represents a flexible band of fabric across the width of which are successively printed the names of the several stations which it is required to indicate.

35 The ends of this band 2 are secured to rollers 3 and 4, the axle pins 5 and 6 of which are mounted in side frames 11, and 40 the band is wound on the rollers to wind off the outer side of one onto the outer side of the other.

Intermediate of the rollers 3 and 4 the band 2 passes over a parallel display and 45 driving roller 7, the axle pin 8 of which is rotatably mounted in the side frames 11. A casing 19 encloses the rollers and band, which casing is apertured opposite the outer side of the display roller 7 to display to the 50 passengers the name of the next station.

The band 2 is held in frictional driving contact with the display roller 7 by an idler roller 9 mounted in slots of the side frames and weighted to hold the band 2 tightly 55 against the roller 7.

On the axle 8 of the display roller is secured a small toothed wheel 14 and on each side of this wheel to move freely on the axle is mounted a pawl lever 12 carrying between the sides of the lever a double-ended pawl 13. Either end of this pawl may be lightly held in engagement with the teeth of the wheel by a coil spring 17 acting on an outward projection from the middle of the pawl.

60 By this pawl lever the roller 7 may be rotated in either direction as desired by bringing either end of the pawl 13 into engagement with the teeth of the wheel 14. The angular movement of the pawl lever necessary to move the band 2 through the distance between the station names is limited by a stop 15 outwardly projecting from a support 16, one end of which is secured to the side frame 11 and the other end carried on 70 an axle 8. The pawl lever 12 is normally held at the backward limit of its movement by a spring 18 and is moved to the other limit by the conductor or other authorized party, by means of a cord connected to the 75 end of the lever.

75 By the mechanism so far described the band 2 may be drawn in successive uniform amounts off one roller 3 or 4 and delivered toward the other 4 or 3.

80 While the roller from which the band is being unwound may be left free to rotate under the pull of the display roller with possibly a slight frictional resistance to prevent over-running, it is necessary to provide 85 a means for rotating the roller toward which the band is delivered and on which it requires to be wound.

85 This means is provided by a driving connection between the display roller 7 and 90 either of the rollers 3 or 4, as required. It consists of a gear wheel 20 secured on the axle 8 of the display roller and a gear wheel 21 and 22 on the axles 5 and 6 respectively of the rollers 3 and 4, and an intermediate 95 gear wheel 23 mounted on a stud secured in a swinging plate 24, by which the wheel 23 may be interposed between the wheel 20 of the display roller and either 3 or 4 as required. This swinging plate is provided 100 with a spring-actuated detent pin 25 that will enter a corresponding aperture 26 to secure it in position for driving either roller 3 or 4 or a detent aperture 27 for securing the intermediate wheel 23 clear of driv- 110

ing connection with either roller, as may be necessary when for any reason the band 2 requires to be run by hand off one roller onto the other.

- 5 As the successive movements of the band 2 over the display roller 7 are necessarily uniform in amount, while the circumference on the roller on which the band is being wound is continually increasing, it is necessary to provide some means of compensation or allowance for this variation, otherwise the band 2 may be strained and torn apart, as the gearing will be rotated through equal angular amounts.
- 10 This difficulty is overcome by connecting the gear wheels 21 and 22 to drive the axles 5 and 6 of the rollers 3 and 4 by friction that will yield by slipping as soon as the band is drawn tight.
- 15 The gears 21 and 22 are therefore not secured on the axles 5 and 6 but are free to rotate thereon against a frictional resistance which normally holds them against rotation. This is attained by mounting each wheel 25 to fit against a conical shoulder 28 and holding it thereagainst by a spring 29 adjustably held against the shoulder by a nut 30 screwed on the end of the axle.
- 20 In use, the indicator is mounted preferably on the leading end of a car fronting the passengers, and as one street or station is passed, the conductor, instead of calling the name of the next station, in a manner which is generally unintelligible, pulls the 30 cord connected to the lever 12 and through the pawl connection to the axle 8 of the display roller 7 the band 2 is moved through the amount necessary to exhibit at the aperture the name of the next street at which 35 the vehicle may stop, and as the band is so moved off the display roller, it is unwound freely from one roller 3 or 4 and is positively wound with a light tension on the other roller 4 or 3.
- 40 If the car is to run back on the same route, the indicator may be transferred to the other end of the car and the pawl 13 and swinging plate 24 are reversed that the same movement of the lever will rotate the display roller 7 in the opposite direction and the other roller 3 or 4, as the case may be, will be rotated as the winding roller. If, as may happen, the car is on a circular route, when it arrives at its designated starting 45 point, the conductor will throw the swinging plate 24 and its intermediate gear 23 into the neutral position, when, by means of a small crank handle on the shaft 8 the band may be continuously run backward to the 50 starting station.

The device, as hereinbefore described, has the following advantageous features over devices of a like character with which I am acquainted.

55 The band, which carries the station names,

is not exposed to excessive tension as the friction by which it is drawn over the display roller 7 is directly set up on that roller, which is intermediate the rollers 3 and 4 from and on which it is wound and unwound. It must be distinctly understood that the band is not drawn over the display roller by the winding roller, which merely winds up the band as delivered to it by the display roller.

70 Again, I believe to be new the provision by which the changing diameter of the winding roller is provided for, the winding roller being driven by a frictional connection between its axle and the positively rotated gears:

75 Also the means for winding the band on either roller 3 or 4 as required, by the intermediate gear 23 mounted on the swinging plate 24.

80 These features produce a particularly effective and simple station indicator.

Having now particularly described my invention, I hereby declare that what I claim as new and desire to be protected in by Letters Patent, is:

1. A station indicator comprising a band of flexible material across which the names of the stations are printed in succession, a frame, winding rollers rotatably mounted within said frame, to which rollers the ends of the band are respectively secured so that the band may be wound on either roller off the other, a display roller rotatably mounted intermediate of and parallel to the winding rollers, around the outer side of which display roller the band passes from one winding roller to the other, means applied to the band on the display roller for imposing a frictional grip between that roller and the band, means for rotating the display roller in either direction, whereby the band is withdrawn from one winding roller and delivered to the other, and means directly operated from the display roller for winding the band upon the roller toward which it is delivered.

110 2. A station indicator comprising a band of flexible material across which the names of the stations are printed in succession, a frame, winding rollers rotatably mounted within said frame, to which rollers the ends of the band are respectively secured so that the band may be wound on either roller off the other, a display roller rotatably mounted intermediate of and parallel to the winding rollers, around the outer side of which display roller the band passes from one winding roller to the other, a free running roller weighted to rest on the upper side of the band as it travels around the display roller, means for rotating the display roller in either direction, whereby the band is withdrawn off one winding roller and delivered to the other, and means directly operated

from the display roller for rotating either winding rollers to wind the band on it as it is delivered from the display roller.

3. A station indicator comprising a band 5 of flexible material across which the names of the stations are printed in succession, a frame, winding rollers rotatably mounted within said frame, to which rollers the ends of the band are respectively secured so that 10 the band may be wound on either roller off the other, a display roller rotatably mounted intermediate of and parallel to the winding rollers, around the outer side of which display roller the band passes from one winding roller to the other, means applied 15 to the band on the display roller for imposing a frictional grip between that roller and the band, means for rotating the display roller in either direction, whereby the band is withdrawn from one winding roller and delivered to the other, said means comprising a toothed wheel secured to the axle of 20 the display roller, an intermediate wheel, a swinging plate on which said intermediate wheel is mounted, said intermediate wheel meshing with the teeth of said toothed wheel and itself having teeth, toothed wheels frictionally mounted on the axles of the winding rollers, all being arranged whereby said 25 swinging plate may be moved to bring the teeth of the intermediate wheels into mesh with those of either of the toothed wheels 30 on the winding rollers, substantially as shown and described.

4. A station indicator comprising a band of flexible material across which the names of the stations are printed in succession, a frame, winding rollers rotatably mounted

within said frame, to which rollers the ends of the band are respectively secured so that the band may be wound on either roller off the other, a display roller rotatably mounted intermediate of and parallel to the winding rollers, around the outer side of which display roller the band passes from one winding roller to the other, means applied to the band on the display roller for imposing a frictional grip between that roller and the band, means for rotating the display roller in either direction, whereby the band is withdrawn from one winding roller and delivered to the other, said means comprising a toothed wheel secured to the axle of 40 the display roller, an intermediate wheel, a swinging plate on which said intermediate wheel is mounted, said intermediate wheel meshing with the teeth of said toothed wheel and itself having teeth, toothed wheels frictionally mounted on the axles of the winding rollers, all being arranged whereby said 45 swinging plate may be moved to bring the teeth of the intermediate wheels into mesh with those of either of the toothed wheels 50 on the winding rollers, substantially as shown and described.

In testimony whereof I affix my signature.

HERBERT J. PENDRAY.
